JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ELECTRICAL APPARATUS.

1,308,158.

Specification of Letters Patent.

Patented July 1, 1919.

Application filed November 18, 1914. Serial No. 872,702.

To all whom it may concern:

Be it known that I, JOSEPH BIJUR, a citizen of the United States, and residing at New York, in the county of New York and 5 State of New York, have invented a new and Improved Electrical Apparatus, of which the following specification is a full disclosure.

This invention relates to auxiliary dynamo-electric apparatus, particularly for use in starting internal combustion engines.

One of the objects thereof is to provide apparatus of the above type of the most simple and practical construction and efficient 15 action.

Another object is to provide in apparatus of the above nature means whereby current is conveniently and simply controlled to give the desired characteristics to the dynamo action.

Another object is to provide in apparatus of the type first mentioned, means whereby the various parts are guarded against injury in action.

25 Other objects will be in part obvious from the annexed drawings and in part indicated in connection therewith by the following analysis of this invention.

This invention accordingly consists in the 30 features of construction, combinations of parts, and in the unique relations of the members and in the relative proportioning and disposition thereof; all as more completely outlined herein.

35 To enable others skilled in the art so fully to comprehend the underlying features thereof that they may embody the same by the numerous modifications in structure and relation contemplated by this invention, 40 drawings depicting a preferred form have been annexed as a part of this disclosure, and in such drawings, like characters of reference denote corresponding parts throughout all the views, of which:—

45 Figure 1 is a semi-diagrammatic elevation showing a central longitudinal section from the dynamo.

Fig. 2 is a diagrammatic plan of electrical circuits and related devices.

50 Referring now to Fig. 1 of the drawings, there is diagrammatically indicated at 1 an internal combustion engine, the crank shaft 2 of which is provided with the fly wheel 3 having thereon the gear 4.

55 Positioned adjacent this fly wheel is the

dynamo comprising armature 5 and field magnets 6, this dynamo being preferably a four-pole machine although certain parts are not shown in the drawing in order to avoid complicating and obscuring the disclosure. 60

Upon the armature shaft 7 is secured a pinion 8 normally lying offset in an axial direction from the gear 4 but adapted upon being moved endwise, as hereinafter described, to come into mesh with this gear. 65

The opposite end of the dynamo shaft is recessed as indicated at 9, and is mounted to slide endwise in its bearing 10; the first end of the shaft sliding in a similar manner in 70 the bearing 11. Recess 9 receives a spiral compression spring 12, the opposite end of which engages a stud or post 13 formed on the dynamo head 14. This spring normally urges the armature with its shaft toward 75 the left, as viewed in Fig. 1 of the drawings, holding gear 8 out of mesh with gear 4 and in this position the armature 5 is out of registry with field magnets 6. Upon the latter receiving current, however, there is 80 a strong endwise pull upon the armature to draw it into registry with the field magnets and thus mesh gear 8 with gear 4.

In the head or auxiliary casing 14, and slidably mounted upon the stud 13, is a cam 85 member 15 of circular cross-section and provided with a flange 16. As the armature slides, as above set forth, the end of its shaft engages this cam member at 17 after it has partially completed its travel, and upon moving through to the right brings the flange into operative relation to the annular flanges 18 provided with a winding 19 whereby they form an iron-clad electromagnet with flange 16 as an armature. 95

The retraction of this flange is brought about by the pressure of a spiral spring 20 compressed between the dynamo head and the cam member at 21.

The outer surface of the round cam member 15 is provided with a flaring or conical portion 22 merging into a substantially cylindrical surface 23. This cam member is engaged by a roller 24 journaled in a lever 25 upon a rock shaft 26 which extends 100 lengthwise of the dynamo passing through the inner head 27 at 28 and adapted to oscillate about an axis parallel to the dynamo shaft. The inner end of rock shaft 26 is provided with a lever 29 extending substan- 110

tially parallel to lever 25 and in the same direction from the rock shaft. This lever is secured at its outer end to the guide 30 of the brush 31, the latter being pressed downwardly for feeding by the usual flat spring 32. A spring 33 is coiled about rock shaft 26 and anchored to the inner head 27, its free end bearing on lever 25 in such direction as to urge the roller 24 toward the cam 5 member 15 and keep it continuously in contact therewith by the rocking of the shaft 26. The commutator 34 is of sufficient length to continuously present opposite the brushes an effective surface during the above 10 noted sliding movement of the armature. Considering now the action of brush 31, it will be seen from the above mechanism that this brush follows the movement of the roller 24 by the oscillation of the shaft 26 15 with the levers 25 and 29 secured thereto. The brush is of such length that with the parts in the normal inoperative position shown and the roller upon the cylindrical portion of the cam, it rests clear of the commutator as indicated in Fig. 1 of the drawings. If now, however, the field magnets be excited and the armature move toward the right, the completion of its path of travel forces the member 15 against the electro- 20 magnet, as above described, and permits roller 24 to ride downwardly upon the conical portion of the cam, thus oscillating shaft 26 and swinging brush 31 against the commutator 34 with a pressure which is determined by the brush feeding spring 32. Upon the cam member 15 moving to the left, however, as hereinafter described, the roller 24 again rides upon the cylindrical portion 25 of cam 15 and raises brush 31 away from 30 the commutator.

With this understanding of the mechanical features of this invention, reference is now made to the diagrammatic showing of Fig. 2.

45 The circuit of a storage battery 35 leads through a switch 36 which may be depressed and closed by the foot pedal 37 of an automobile. From this point the circuit leads to the positive brush 38, which is of the ordinary construction, positioned at the neutral point and not shown in Fig. 1 in order to avoid complicating the latter. The negative brushes are two in number, one of which is the brush 31, above referred to, disposed opposite the neutral point of the commutator; the remaining negative brush 39 is positioned far from the neutral point of the generator and may be even adjacent the positive brush 38. Brush 39 is slidably 50 mounted in a guide 40 formed on a lever arm 41 extending from the rock shaft 26 in a direction substantially opposite from the arm 29 in such manner that as the rock shaft is swung as above described to throw brush 55 31 toward the commutator 34, it will swing

brush 39 away from the commutator immediately after brush 31 has made engagement. It is to be noted that both brushes are urged toward the commutator by the spiral springs 32 and that a space 42 is provided 70 between the brush guide and the portion 43 which it engages to lift the brush in order to provide for the wearing away of the brush in use.

From the negative brush 39 the circuit 75 leads through a resistance element 44 and is then joined by conductor 45 leading directly from brush 31, the circuit then passing through the series field winding 46 of the dynamo to the remaining pole of the 80 battery 35.

Shunted about the dynamo is a circuit 47 leading through the winding 19 on the electromagnet above described.

The action and method of use of the above 85 apparatus is substantially as follows:—

The gears 8 and 4 normally lie out of mesh or operative relation, and it may here be noted that the term "gear" is used throughout in a broad sense to comprehend 90 any type of toothed or friction connection. Upon pedal 37 being depressed, the switch member 36 completes a circuit which passes to the motor through positive brush 38 and thence through the negative auxiliary brush 95 39, resistance 44 and field winding 46 to the battery. With the current thus passing through the motor armature and leaving the commutator through the brush 39 materially spaced from the negative neutral point, 100 there is obviously a marked distortion of and lack of symmetry to the magnetic field which the armature windings create. This is due largely to the fact that the current in the windings comprehended between brush 105 39 and the neutral point opposite 31, passes in such direction as to oppose or retard the rotary movement of the armature by generating a reverse magnetomotive force. For this reason, there is imparted to the armature a relatively weak rotative force or torque, although the pull of the field magnets in an endwise direction upon the armature is considerable. This strong end- 110 wise pull quickly brings the slowly turning 115 pinion 8 into mesh with gear 4, the contiguous ends of the teeth being suitably rounded or pointed if desired. Thereupon the armature shaft forces the cam member 15 to the right, with reference to Fig. 1 of the drawings, permitting the roller 24, which is diagrammatically indicated as offset in Fig. 2, for clearness, to ride downwardly upon the cam member 15. This action swings the levers 29 and 41, as above described, bringing 120 brush 31 against commutator and immediately thereafter withdrawing brush 39. There is now exerted a strong rotary force upon the armature for not only is the starting current undiminished by resistance 44 125 130

- but the negative brush is properly positioned at the neutral point, thus eliminating the impeding action of brush 39. The motor now exerts its full torque and quickly starts engine 1 which upon speeding up rotates armature 5 at such rate that its counter-electromotive force quickly cuts down the strength of the field 6 and permits spring 12 to throw the armature to the left, bringing pinion 8 out of mesh with gear 4. If at this stage the switch 36 has been permitted to rise, the cam member 15 will also move to the left being released by the electromagnet and retracted by spring 20.
- This action, which is the reverse of that above described, first permits auxiliary brush 39 to come into operative relation to the commutator and then withdraws brush 31. If, however, the switch 36 is held closed after the gears have broken engagement, the action of magnet 19 holds the cam member in the position into which it has been moved and brush 31 remains in contact with the commutator. The motor is thus maintained at such a high rate of speed that its counter-electromotive force precludes the development of such field strength by the magnet 6 as to overcome the spring 12 and throw gear 8 toward the rapidly rotating gear 4.
- In the movement of armature 5 toward the right to bring the gears into meshing position, its movement is opposed only by the spring 12 for even after it has engaged and is moving the cam member 15 the effect of spring 20 is largely neutralized by the attraction of the electro-magnet upon the flange 16. Due to this action, the parts may be so proportioned that there is a material preponderance of magnetic pull of the field magnets to bring the armature into registry and the meshing of the gears is rendered correspondingly positive and reliable. This effect is gained, moreover, without sacrificing the reliability of the demeshing action when current is cut off, for in such case the windings 19 are deenergized and both springs 20 and 12 co-operate in forcing the armature toward the left and the pinion 8 out of mesh with gear 4. Another feature of the action of this apparatus which may not be obvious is that armature 5 moving toward the right as the gears are brought into mesh has, as above noted, a material travel before engaging the cam member 15 and thus delivers to the latter, by reason of this momentum, a hammer blow which overcomes the static friction of the sliding parts and aids in rendering the operation of the mechanism more certain.
- It will also be seen that by the use of this apparatus the burning of the contacts of the switch 36 is materially reduced, for at whatever time this switch is permitted to open the current is held at a low value either by the resistance 44 or by the considerable counter-electromotive force of the dynamo, due to the action of the high-speed brush 31. It is also to be understood that the swinging of the brushes with consequent increase in torque of the armature, does not await the completion of the sliding movement but occurs whenever the gears are securely in mesh and nothing herein is to be construed to the contrary.
- It will thus be seen that the parts are not only guarded against mechanical injury but the electrical injury is reduced to a minimum, and the construction is simple and its action reliable and efficient.
- As many changes might be made in the above construction, and as many apparently different embodiments might be made of this invention without departing from the scope thereof, it is intended that all features herein described or shown in the accompanying drawings shall be interpreted as illustrative and not in a limiting sense.
- Having thus revealed this invention, I claim as new and desire to secure the following combinations of elements, or equivalents thereof, by Letters Patent of the United States:—
1. In apparatus of the class described, in combination, an internal combustion engine, a dynamo provided with an endwise slideable armature normally out of registry with its field magnets, gearing positioned between said engine and said dynamo adapted to form a power transmitting connection therebetween as said armature slides, a brush substantially opposite one neutral point of the commutator of said dynamo, a brush substantially opposite a complementary neutral point, a brush opposite a point of said commutator angularly spaced from either neutral point, means adapted to move second and third brushes alternatively into contact with the commutator and a device controlled by the sliding movement of said armature and acting upon said last means to render said third brush operative during said sliding movement and said second brush operative at a later stage of said movement.
  2. In apparatus of the class described, in combination, an internal combustion engine, a dynamo provided with an endwise slideable armature normally out of registry with its field magnets, gearing positioned between said engine and said dynamo adapted to form a power transmitting connection therebetween as said armature slides, a brush substantially opposite one neutral point of the commutator of said dynamo, a brush substantially opposite a complementary neutral point, a brush opposite a point of said commutator angularly spaced from either neutral point, a device adapted to move said second and third brushes alternatively against

- said commutator, and a cam controlling the action of said device and controlled by the sliding movement of said armature.
3. In apparatus of the class described, in combination, an internal combustion engine, a dynamo provided with an endwise slideable armature normally out of registry with its field magnets, gearing positioned between said engine and said dynamo adapted to
- 10 form a power transmitting connection therebetween as said armature slides, a brush substantially opposite one neutral point of the commutator of said dynamo, a brush substantially opposite a complementary neutral
- 15 point, a brush opposite a point of said commutator angularly spaced from either neutral point, a device adapted to move said second and third brushes alternatively against said commutator, a cam controlling the action of
- 20 said device and controlled by the sliding movement of said armature, and electromagnetic means adapted to prevent reverse action of said brushes as said armature returns to normal position.
- 25 4. In apparatus of the class described, in combination, an internal combustion engine, an electric motor, means adapted to drive said engine from said motor, and means adapted to lead current to one brush of said
- 30 motor through a resistance and subsequently lead it directly to another brush without said resistance.
5. In apparatus of the class described, in combination, an internal combustion engine, an electric motor, means adapted to drive said engine from said motor, and a single device adapted successively to lead current to said motor through one brush and a resistance element in series therewith and
- 40 thereupon directly through another brush.
6. In apparatus of the class described, in combination, an internal combustion engine, an electric motor, means adapted to drive said engine from said motor, means adapted
- 45 to lead current to said motor through one brush having a resistance in series therewith, and a device adapted thereafter to move another brush into contact with the commutator of said motor and lead current directly
- 50 thereto.
7. In apparatus of the class described, in combination, a dynamo having an armature which is slideable endwise with respect to its field magnets, an internal combustion engine, gearing adapted upon said armature sliding to connect said engine with said dynamo, a compound spring, and means adapted to cause said spring to oppose movement of said armature toward registry with its field
- 55 magnets with a certain force and to tend to move it out of registry with a greater force.
8. In apparatus of the class described, in combination, a dynamo having an armature which is slideable endwise with respect to its
- field magnets, an internal combustion engine, 65 gearing adapted upon said armature sliding to connect said engine with said dynamo, resilient means tending to urge said armature out of registry with its field magnets, and means adapted to reduce the effect of said resilient means during the movement of said armature toward registry with its field magnets.
9. In apparatus of the class described, in combination, a dynamo having an armature 75 which is slideable endwise with respect to its field magnets, an internal combustion engine, gearing adapted upon said armature sliding to connect said engine with said dynamo, a spring tending to slide said armature out of registry with its field magnets, a second spring tending to aid said first spring in said action, and means tending to neutralize the effect of said second spring as said armature slides toward registry with its field magnets. 80
10. In apparatus of the class described, in combination, a dynamo having an armature which is slideable endwise with respect to its field magnets, an internal combustion engine, gearing adapted upon said armature 90 sliding to connect said engine with said dynamo, means adapted upon actuation to affect the current led to said armature, and a device adapted to actuate said last means and positioned to be engaged and actuated 95 by a part controlled by said armature during its sliding movement, said part being so formed as to make said engagement after said armature has started its sliding movement.
11. In apparatus of the class described, in combination, an internal combustion engine, an electric motor, means adapted to drive said engine from said motor, a source of current, a pair of brushes positioned opposite the commutator of said motor, one of which is connected with said source of current in series with a resistance element and the other of which is connected with said source of current independently of said resistance 105 element, and means adapted to lead current from said source to said motor first through said first brush and thereafter through said second brush.
12. In apparatus of the class described, in combination, an internal combustion engine, an electric motor, means adapted to drive said engine from said motor, a source of current, a pair of brushes positioned opposite the commutator of said motor, one of which is connected with said source of current in series with a resistance element and the other of which is connected with said source of current independently of said resistance element, and a device adapted upon said motor 110 being started to admit current thereto first through said first brush and thereafter through said second brush and as the motor
- 120
- 125

is stopped to cut off current first through said second brush and then through said first brush.

13. In apparatus of the class described, in combination, an internal combustion engine, an electric motor, means adapted to drive said engine from said motor, a source of current; a pair of brushes positioned opposite the commutator of said motor, one of which is connected with said source of current in series with a resistance element and the other of which is connected with said source of current independently of said resistance element, and means adapted to admit current to said motor as it is started through said first brush and thereafter to move said second brush against the commutator of the motor.
14. In apparatus of the class described, in combination, an internal combustion engine, an electric motor, means adapted to drive said engine from said motor, a source of current, a pair of brushes positioned opposite the commutator of said motor, one of which is connected with said source of current in series with a resistance element and the other of which is connected with said source of current independently of said resistance element, means adapted as the motor is started
15. In apparatus of the class described, in combination, an internal combustion engine, an electric motor, means adapted to drive said engine from said motor, a source of current, a pair of brushes positioned opposite the commutator of said motor, one of which is connected with said source of current in series with a resistance element and the other of which is connected with said source of current independently of said resistance element, means adapted to lead current thereto through said first brush, and a device adapted subsequently to move said second brush into engagement with the commutator.

16. In apparatus of the class described, in combination, an internal combustion engine, an electric motor, means adapted to drive said engine from said motor, a source of current, a pair of brushes positioned opposite the commutator of said motor, one of which is connected with said source of current in series with a resistance element and the other of which is connected with said source of current independently of said resistance element, means adapted as the motor is started to lead current thereto through said first brush, and a cam actuated device adapted thereafter to move said second brush into engagement with the commutator and to cause it to move away from the commutator when the motor is stopped.

In witness whereof, I hereunto subscribe my name, as attested by the two subscribing witnesses.

JOSEPH BIJUR.
